UNITED STATES PATENT OFFICE.

JOHN BIGELOW, OF MINNEAPOLIS, MINNESOTA, ASSIGNOR TO UNION SPECIAL MACHINE COMPANY, OF CHICAGO, ILLINOIS, A CORPORATION OF ILLINOIS.

SEWING-MACHINE CUTTING MECHANISM.

1,117,160.

Specification of Letters Patent. Patented Nov. 17, 1914.

Original application filed May 22, 1900, Serial No. 17,552. Divided and this application filed July 8, 1904. Serial No. 215,795.

To all whom it may concern:

Be it known that I, JOHN BIGELOW, a citizen of the United States, residing at Minneapolis, in the county of Hennepin, 5 State of Minnesota, have invented certain new and useful Improvements in Sewing-Machine Cutting Mechanism, of which the following is a description, reference being had to the accompanying drawing, and to 10 the letters and figures of reference marked thereon.

This application is a division of my application filed in the United States Patent Office May 22nd, 1900, Serial No. 17,552, and 15 patented December 31, 1907, No. 875,814.

The present invention relates to the mechanism for cutting the threads between any two consecutive sacks, but it will be understood that so far as the cutting members 20 are concerned, they might coöperate in the manner set forth to sever a continuous strip of material.

So far as the main features of the apparatus are concerned, reference is made to the 25 aforesaid parent application, but the present invention consists in certain matters hereinafter described and referred to in the appended claims.

The invention is illustrated in the accompanying drawings, in which,

Figure 1 is a front elevation of a filled bag sewing machine embodying my invention; Fig. 2 is a vertical cross section on the line v^2-v^2 , of Fig. 1; Fig. 3 is an end view 35 of the cutter or clipper; Fig. 4 is a plan view thereof; Fig. 5 is a section on line x^5-x^5 , Fig. 3; Fig. 6 is a section on line $z-z$, of Fig. 3; Fig. 7 is a view similar to Fig. 3, but showing the opposite side or end 40 of the clipper; and Fig. 8 is a vertical section on the line $y-y$ of Fig. 4. Fig. 9 is a horizontal section on line $9-9$ of Fig. 1.

As above stated, the present invention relates to the mechanism employed for automatically cutting the thread or chain of 45 stitches between the bags; that is, the bag that has been sewed and the one in the machine. This mechanism is preferably arranged at the delivery end of the work plate. 50 Either the bracket 34, or the arm 51 which extends back of the sewing head is provided with a plate 119, and to this is attached a block 120 having three arms 121, 122 and 123, the latter being provided with the up-

wardly extending arms 123' and 123''. The 55 arm 121 carries the pivot pin 124, for the yoke lever 125, the lower end of which engages with the end of the arm 126, arranged on the shaft 105, and opposite to the arm 107. The upper end of the lever 125 60 is connected by a link 128 to the upper end of a short lever 129, the lower end of which is pivoted on the pin 130 in the side of the block 121. These parts between the shaft 105 and the pin 130, constitute the means 65 for setting the clipper when the machine is started by the throwing of the knee lever 106. The clipper comprises the knife or crushing edge 132, and the cylinder 133 upon which the knife closes. The cylinder 133 is 70 fastened in a pocket that is drilled therefor in the bottom of the arm 123, which pocket cuts through the face of the arm or block so that the surface of the hardened steel cylinder projects slightly beyond the face 75 of the arm 123. The cylinder is held in place by a screw 134 upon loosening which the cylinder may be taken out or turned slightly to present a fresh surface to the cutting edge of the knife. The knife 132 80 is mortised into the weighted end 135 of the clipper arm 136. The mortise or pocket 135' for the knife 132 is preferably made partly in the solid part of the arm 136 and partly in the cap or block 135'' upon the inner side 85 thereof. The knife is secured by the adjusting screw 137 and the set screw 138. The clipper arm 136 is provided with bosses or a sleeve 139 journaled upon the short shaft 140 extending between the upper 90 ends of the arms 123' and 123''. On the same shaft 140 is the escapement member 141 provided with a hand setting lever 142. The sleeve 139 and the member 141 carry the arms 143 and 144 respectively. These 95 arms are held together by the buffer-spring 145 arranged between the arm 143 and the head of a curved bolt or pin 146 that is fastened in the part 144.

147 is a strong spring coiled around the 100 boss or hub of the escapement member 141 and fastened to said member and to the arm 123' so as to throw the member forward and thereby throw down the clipper arm 136. The member 141 is provided with a laterally 105 extending lug 148, which, when the member is raised or set with the arm 136 in its raised position, is removed from the arm 123', but

when the member 141 is released said lug 148 will strike said arm 123 before the knife of the clipper strikes the cylinder or cutting surface 133, after which the clipper arm 5 continues its movement because of its momentum. At this time the spring 145 is compressed, and the knife strikes the cylinder 133 and is then instantly withdrawn to the position shown in Fig. 3 by the reflex 10 action of the spring 145.

149 is a stop screw provided on the clipper arm 136 to strike the face of the block when the knife is thrown down, see Fig. 8. By means of the screw 149 the device is so 15 adjusted that the sharp edge of the knife just meets the surface of the hardened cylinder 133 and then rebounds, so that the knife is not dulled except by the actual wear of the thread thereon. As the thread 20 or chain of stitches comes from beneath the presser foot 50 it is held up by the bag which has passed the clipper, and by a small ledge 150 that is provided upon the work-plate so that the thread will always lie or 25 stretch across the cutting surface 133 ready for the descent of the knife, (see Figs. 3, 7 and 9).

The lever 129 before referred to, carries the short trigger lever 151, the rear end of 30 which is weighted and the forward end of which is notched, (see 152) to engage the shoulder 153 on the side of the escapement member 141. This takes place when the knee shifter 106 is thrown to move forward 35 the link 128 and the lever 129. The trigger 151 then engages with the escapement member 141 to rotate the same until it is caught and held by the latch lever 154, the forward end of which engages a shoulder 155 on the 40 member 141, holding the member under the tension of the spring 147 with the clipper arm in a raised position. When the parts are in these positions, it is only necessary to free the latch 154 to allow the knife to 45 descend and cut or clip the thread and immediately open so as not to interfere with the next bag. The release of the latch is accomplished automatically and depends upon the passage of the bag.

50 156 is a rock shaft arranged on the arms 122 and 123 adapted to be operated by the gravity arm or trip 157. Said shaft 156 also carries the adjustable rocker arm 158 provided with the cross-pin 159 that is 55 adapted to successively engage the pins 160 and 161 in the rear ends of the levers 151 and 154, thus when the arm 157 drops the setting trigger 151 will first be moved out of the path of the shoulder 153 of the 60 escapement member and then the latch 154 will be thrown to release said member and the knife. The arm 157 is extensible, as shown in Figs. 1 and 3 to 8, and swings below the level of the work plate of the sewing head, so that the arm will be struck

and raised by a bag as it emerges from the sewing head (see Figs. 1 and 7). The clipper having previously been set by the starting of the sewing machine the moment that the sewed bag moves out from beneath the arm 157 said arm will drop or swing back of its own weight, and instantly release the knife to cut the thread between the two bags. This clipper is in no wise 70 a burden or drag upon the sewing mechanism. It is not a driven device, and the only power necessary for its operation is derived from the shifter lever which the operator throws with his leg or knee against the resistance of the shifter spring 115 and 75 the small spring 147 of the clipper.

The operation of my device will be obvious. As the knee lever 106 is operated to start the machine the clipper carrying the knife or crushing edge will be raised 80 by the lever 129 through the trigger lever 151. The clipper is held in its elevated position or set by the latch lever 154. The latch is operated by the arm or trip 157, as it drops from the bag and thus releases the 85 clipper which is moved by the spring 147 to sever the thread. The spring 145 immediately after the severing action, moves the clipper away from the cylinder sufficiently to allow the passage of the 90 succeeding sack.

As the sewed bag leaves the sewing mechanism a chain of stitches will be formed between the two bags, and this chain will draw across the ledge upon the work plate 100 and across the clipper block in readiness to be cut by the knife when the arm 157 falls, after having been previously raised by the passing of the bag. The clipper may be set by hand and released by hand, if 105 desired, and the machine may be stopped at any time by throwing the hand trip 117 to disengage the trigger 110, whereupon the bag may be removed from the machine after lifting the presser foot.

Having thus described my invention, what I claim as new, and desire to secure by Letters Patent is:—

1. In an apparatus for sewing filled bags, sewing mechanism and a cutting apparatus 115 controlled by the passage of a bag for severing the threads between the bags including two coöperating members, which when in operative position embrace between them the thread to be severed, means for causing 120 coöperative action between said members, and means operating immediately after the severing action for positioning one of said members to allow the passage of the succeeding bag, substantially as described.

2. In a filled bag sewing machine, the combination, with sewing mechanism, of a clipper arranged upon the delivery side of said head, and including a knife, means for operating the same, and a cylinder lying in 125

the plane of movement of the cutting edge of the knife and coöperating therewith, substantially as described.

3. In a filled bag sewing machine, the combination with sewing mechanism, a clipper for severing the threads between bags including a rebounding knife, means for operating said knife, a supporting frame, and a hardened cylinder carried by 10 said frame and lying in the plane of movement of said knife.

4. In a filled bag sewing machine, the combination, with a sewing mechanism, of a clipper for severing the thread between two 15 bags including a rebounding knife, a frame therefor, a hardened cylinder set into said frame with its surface projecting therefrom, a fastening device for said cylinder which permits the presenting of new surfaces upon 20 said cylinder to said knife, and means for operating said knife, substantially as described.

5. In a filled bag sewing machine, the combination, with sewing mechanism, of a 25 clipper for severing the thread between two bags including a frame, a rebounding knife mounted on said frame, a stop for said knife, a hardened surface on said frame lying in the plane of movement of the cutting edge of the knife and coöperating therewith, substantially as described.

6. In a filled bag sewing machine, the combination with sewing mechanism, of a clipper for severing the thread between two 35 bags including a frame, an arm pivoted thereon, a knife carried by said arm, an adjustable stop for said arm, a hardened piece in said frame, a spring operated member connected with said arm, and means for 40 setting and releasing said member, substantially as described.

7. In a filled bag sewing machine, the combination, with sewing mechanism, of a clipper for severing the thread between two 45 bags, including a knife, an arm supporting said knife, a spring operated member for actuating said arm, a setting pawl, means for setting the same when the sewing mechanism is started, a latch for said spring operated member, and a trip for disengaging 50 said latch, substantially as described.

8. In a filled bag sewing machine, the combination, with sewing mechanism, of a clipper for severing the thread between two 55 bags including a knife, a setting pawl, a latch pawl and a swinging arm or trip adapted to successfully operate said setting and said latch pawls, substantially as described.

9. In a filled bag sewing machine, the combination, with sewing mechanism, and feeding mechanism, of a clipper comprising a knife, and operating and controlling means therefor, including devices adapted to be 60 set when the sewing mechanism is started,

and a trip for said devices adapted to release the clipper upon the passage of the bag by said devices.

10. In a filled bag sewing machine, a clipper comprising a crushing member, a 70 coöperating member, means for operating said crushing member, whereby the connecting loops of two bags are severed by a single crushing blow, said operating means including a trip falling from the top of one of the 75 bags as the bag passes said trip.

11. In a bag sewing machine, a clipper comprising a wedge-shaped cutter, an anvil lying in the plane of movement of the cutting edge and coöperating therewith, 80 means for operating said cutter including devices controlled by the passage of the bag, and means for moving the cutter out of severing position to allow the passage of the succeeding bag.

12. In a bag sewing machine, a clipper comprising a wedge-shaped cutter, an anvil, means for operating said cutter including devices controlled by the passage of the bag, and means independent of the operating 90 means for withdrawing the cutter from the path of the bags.

13. In a bag sewing machine, a clipper comprising a wedge-shaped cutter, an anvil, means for operating said cutter including 95 devices controlled by the passage of the bags, and spring controlled means operating to withdraw the cutter from the path of the bags.

14. In mechanism of the class described, 100 the combination with severing mechanism movable from a set position, of means for moving it from its set position, means for holding the severing mechanism in its set position against the action of the moving means, and a trip for operating the holding means to release the severing mechanism and permit its actuation by the moving means, said trip being normally held 105 inoperative by the article to be severed.

15. In mechanism of the character described, the combination with severing mechanism movable from a set position, of a spring for moving it from said set position, means for holding the severing mechanism in its set position against the action 115 of the spring, and a trip for operating the holding means to release the severing mechanism and permit its actuation by the spring, said trip being normally held inoperative 120 by the article to be severed.

16. In mechanism of the class described, the combination with a reciprocatory cutting member movable from and to a set position, of a spring for moving it from its set position, means for holding the member in its set position against the action of the spring, said means including a dog, and article supported trip that operates the dog to 125 release the cutting member.

17. In mechanism of the class described, the combination with a cutting member movable from and to a set position, of means for holding the member in its set position, 5 means for moving it to its set position, and a trip for disengaging the member from its holding means, said trip being normally held inoperative by the article to be cut.
18. In mechanism of the class described, 10 the combination with a movable cutting member, of means for moving it in one direction, a device for holding the member against movement by said means, means for moving the cutting member into engagement with the holding device, and means controlled by the article to be cut for releasing said member from the holding device.
19. In mechanism of the class described, 15 the combination with a movable cutting member, of a spring for moving the member in one direction, a device for holding the member against movement by said spring, means for moving the cutting member into engagement with the holding device against the tension of the spring, and means controlled by the article to be cut for releasing the cutting member from the holding device.
20. In mechanism of the class described, 20 the combination with article severing means, of means for moving the severing means, mechanism for holding said article-severing means against operative movement by the moving means, and means held inactive by the articles to be severed for releasing the severing means from the holding mechanism.
21. In a sewing machine, the combination 25 of stitch forming mechanism for stitching articles and forming a connecting chain of stitches between the same, a chain severing member, and means operating independently of the article for holding said severing member from engagement with the chain and means controlled by the articles being stitched for releasing said holding means.
22. In a sewing machine, the combination 30 of stitch forming mechanism for stitching articles and forming a connecting chain of stitches between the same, a chain severing member, means for operating said member including a spring, means operating independently of the articles being stitched for holding said severing member from engagement with the chain, and means controlled by the articles being stitched for releasing said holding means.
23. In a sewing machine, stitch-forming mechanism for stitching articles and forming a connecting chain of stitches between the same and a chain-severing member, a spring for impelling the same in the direction of the chain, a trip for holding said 35 member with the spring under stress, and automatic mechanism for releasing the trip.
24. In a sewing machine, stitch-forming mechanism, a severing member, means for operating said member including a spring, 70 a trip for holding the same with the spring under stress, and means under the control of the fabric for moving the trip to release position.
25. In a sewing mechanism, stitch-forming 75 mechanism, a severing member, means for operating said member including a spring, a trip for holding the same with the spring under stress, and a trip-releasing means arranged to engage with the fabric adjacent 80 to the presser foot of the machine.
26. In a sewing machine, chain stitch-forming mechanism, a chain-severing member, a spring for impelling the same in the direction of the chain, a trip for holding 85 said member with the spring under stress, and a trip-releasing means held in inoperative position by engagement with the article being sewed.
27. A sewing machine including in combination, stitch-forming mechanism, feeding mechanism and thread-severing devices, said thread-severing devices comprising an anvil and a movable cutting member, said movable cutting member being located at 90 right angles to the line of feed and said anvil receiving the impact of said movable member and means controlled by the article being stitched for operating said movable member. 100
28. A sewing machine including in combination, stitch-forming mechanism, a feeding mechanism, thread-severing devices including an anvil located in the line of feed and operating to support the thread between stitched articles, a movable cutting member, and means controlled by the article being stitched for operating said movable member. 105
29. In a sewing machine, a severing member, means for operating the same including a spring, a trip for holding the same away from the chain, a lever movable independently of the trip in one direction and positively engaging said trip when moving in the opposite direction, and a fabric-controlled means through which movement is imparted to said trip. 110
30. In a sewing machine, a severing device, means for operating the same including a spring, means for moving said severing device away from the thread, means for locking the severing device in its withdrawn position, and automatic means for releasing the severing device. 115
31. A filled bag sewing machine including in combination a supporting frame, a support for the filled bags projecting forwardly from the front face of said supporting frame, a sewing head overhanging said 120 125 130

support, stitch forming mechanism carried by said sewing head for stitching filled bags and for forming a connecting line of thread between the same, and means for severing 5 said line of thread connecting the filled bags, including an arm movably supported in rear of the plane of travel of the mouth of the bags being stitched so as to move in a plane substantially at right angles to the 10 path of travel of the bags, said arm having a severing member, a coöperating severing member located in rear of the plane of travel of the mouth of said bags, and means for actuating said movable arm.

15 32. A filled bag sewing machine including in combination a supporting frame, a support for the filled bags projecting forwardly from the front face of said supporting frame, a sewing head overhanging said 20 support, stitch forming mechanism carried

by said sewing head for stitching the filled bags and forming a connecting line of thread between the same, and means for severing the line of thread connecting the filled bags including a supporting arm pivoted in rear of the plane of travel of the bags being stitched to swing in a plane substantially at right angles to the connecting line of thread, said arm having a severing member, a coöperating severing member 25 also located in rear of the plane of travel of the mouth of said bag, and means mounted on said supporting frame for actuating said pivoted arm.

30 In testimony whereof I affix my signature 35 in presence of two witnesses.

JOHN BIGELOW.
